L. K. FULLER.

ORGAN CASE.

No. 16,497.

Patented Feb. 2, 1886.

Fig. 1.

Fig. 2.

UNITED STATES PATENT OFFICE.

LEVI K. FULLER, OF BRATTLEBOROUGH, VERMONT, ASSIGNOR TO THE
ESTEY ORGAN COMPANY, OF SAME PLACE.

DESIGN FOR AN ORGAN-CASE.

SPECIFICATION forming part of Design No. 16,497, dated February 2, 1886.

Application filed October 5, 1885. Serial No. 179,069. Term of patent 14 years.

To all whom it may concern:

Be it known that I, LEVI K. FULLER, a citizen of the United States, residing at Brattleborough, Windham county, Vermont, have 5 invented or produced a new and original Design for an Organ-Case, of which the following is a specification.

My design is clearly shown in the accompanying engravings, of which Figure 1 is a 10 perspective view of the front of the case, and Fig. 2 is a perspective view of the rear thereof.

The principal feature of my design is the rounded corner *a* at the junction of the back and top of the case, as shown in Fig. 2. This 15 rounded corner is in substance a quarter-section (more or less) of a cylinder, which is interposed between the back and top, joining them through the medium of offsets or rabbets, as shown, by which the surfaces are interrupted.

20 The top is flat, and the ends *E E* of the case extend somewhat above the top, producing in connection with the rounded corner the effect shown. The back of the case is, in general, of a plane surface, the lower portion of which is

25 subdivided into four vertical panels, *B B*, and the upper portion of which has two recessed panels, *C C*. The four panels, *B B*, are crossed by a horizontal band of ornamental figure, as shown, which is interrupted by the upright 30 styles, and appears only on the panels. The panels *C C* are similarly crossed by a horizontal band or pattern consisting of three parallel lines, with cross-lines and dots, disposed as shown. The consoles consist of flat pieces *D*

35 *D*, standing in vertical planes at opposite ends of the key-board projection, and cylindrical pillars beneath them. The pieces *D* beneath the key-board projection are tapered until they are nearly square in cross-section where 40 they join the pillars. At the junction of the

pillars with the pieces *D* there is a cube-like ornament, *c*, and lower down, at about the middle of each pillar, there is a twisted enlargement, *d*, all as shown in Fig. 1.

I claim—

1. The design for an organ-case, consisting of the back of the case, the flat top, and the rounded corner or quarter-cylinder intervening between the back and top, substantially as shown in the accompanying engravings. 45

2. The design for an organ-case, consisting of the back of the case, the flat top, the elevated ends, and the quarter-cylindrical rounded corner intervening between said back and top, substantially as shown in the accompanying 50 engravings. 55

3. In a design for an organ-case, the design for the back of the case, consisting of the vertical panels *B B* below and the horizontal panels *C C* above, with a horizontal ornamental band crossing the lower panels and a pattern of horizontal lines crossing the upper panels, substantially as shown in Fig. 2 of the accompanying 50 illustrations. 55

4. In a design for an organ-case, the design 65 for the console, substantially as shown, the same consisting of a flat piece, *D*, at the end of the key-board projection, tapering beneath the key-board projection, and joining a cylindrical pillar through the medium of a cubical ornament, *c*, and a twisted enlargement, *d*, at the middle of said pillar. 70

In witness whereof I have hereunto signed my name in the presence of two subscribing witnesses.

LEVI K. FULLER.
